UNITED STATES PATENT OFFICE

153,202

DESIGN FOR A FUNNEL

Louis L. Beller, Oakland, Calif.

Application June 20, 1947, Serial No. 139,839

Term of patent 14 years

(Cl. D44—29)

To all whom it may concern:

Be it known that I, Louis L. Beller, a citizen of the United States, and a resident of Oakland, in the county of Alameda and State of California, have invented a new, original, and ornamental Design for a Funnel, of which the following is a specification, reference being had to the accompanying drawings, forming part thereof, wherein

Figure 1 is a perspective view of a funnel embodying my new design.

Figure 2 is a top view of the funnel.

Figure 3 is a bottom view of the funnel.

Figure 4 is a fragmentary and partial sectional view of the funnel.

I claim:

The ornamental design for a funnel, substantially as shown.

LOUIS L. BELLER.
